NANOSECOND SPECTRAL SOURCE SYSTEM

J. Perry Smith, Hawthorne, and Ulf R. Helgesson, Sherman Oaks, Calif., assignors to TRW Inc., Redondo Beach, Calif., a corporation of Ohio

Filed Jan. 24, 1966, Ser. No. 753

Term of patent 14 years

(Cl. D26—1)

Fig. 1.

Fig. 2.

Fig. 3.

Fig. 4.

Fig. 6.

Fig. 7.

FIGURE 1 is a front elevational view of a nanosecond spectral source system showing our new design;

FIGURE 2 is a right side elevational view thereof;
FIGURE 3 is a rear elevational view thereof;
FIGURE 4 is a left side elevational view thereof;
FIGURE 5 is a plan view thereof;
FIGURE 6 is a front perspective view thereof; and
FIGURE 7 is a rear perspective view thereof.

We claim:

The ornamental design for a nanosecond spectral source system, substantially as shown.
